UNITED STATES PATENT OFFICE

HERMANN SCHUBERT, OF RADEBEUL NEAR DRESDEN, GERMANY

CENTRIFUGAL MACHINE

Application filed September 7, 1932, Serial No. 631,971, and in Germany February 5, 1930.

The known continuously working centrifugal machines or disintegrators have the disadvantage that the centrifuged solid material must be removed by means of scraping knives or the like passing over the inner mantle surface, whereby the parts rubbing against each other will show an early wear. In order to avoid this, it has already been proposed to give the drum-mantle a cone-like shape and this in such a manner that the mantle will increase from the supply-side to the discharge side. In this case, however, one is forced to arrange the drum mantle in a certain angle of inclination which will have to be adapted to the quality of the material to be centrifuged and this in such a manner that the material will neither slide too quickly nor too slowly across the drum mantle towards the discharge side. As, however, the qualities of the material perpetually change and also the surface of the drum mantle will not remain evenly smooth, it is practically impossible to obtain a required constant speed of the discharge movement.

The present invention has the purpose of building up a centrifugal drum in such a manner that the inclination of the drum in respect to the increase of radius of the drum mantle may also during the centrifuging process be adjusted at will according to the given qualities of the material to be centrifuged and the nature of the mantle surface, so that the centrifugal machine will be able to work without any special discharging device.

This effect is obtained according to the invention with a centrifuging drum having its mantle made up of a number of parts tightly connected together, which are pivotally arranged around axes lying transversally to the axis of rotation of the drum, by arranging the pivoted mantle parts between parallel tightening guiding surfaces in such a manner that while keeping the mantle closed, the inclination of the mantle parts may be adjusted at will.

The invention is shown on the annexed drawing by way of example in different modes of construction, in which:

Fig. 1 shows the centrifugal machine in vertical cross-section,

Fig. 2 presents a plan view,

Fig. 3 shows a special construction of the segments forming the drum mantle, and

Figs. 4 and 5 show a further modified construction of said segments.

As will be seen by Figs. 1 and 2 the drum mantle may consist of any desired number of parts, for instance of the four parts *a*, *b*, *c*, *d*, which on an upright arrangement of the centrifugal machine are each pivotally and adjustably mounted to swing about the horizontal axes *f*.

The single segments *a*, *b*, *c*, *d*, are according to the invention, as will be seen by Fig. 2, closely set between the guides *e*, so that the cone of the drum mantle may, from the side of the supply-hopper to the side of the discharge, be at any time during the centrifuging process regulated and fixed within the practically necessary limits. By means of the guides *e* it is ensured that the material notwithstanding the regulation and adjustment of the mantle parts will not be able to escape sideways from the latter and that thus the mantle at all times remains closed. The adjustment of the mantle parts *a*, *b*, *c*, *d*, set between the guides *e*, may be effected in any required manner and by any desired means.

Fig. 3 shows a special mode of constructing the mantle parts *a*, *b*, *c*, *d*. Each of these parts consists, in a manner known per se, of an endless band *t* guided around two axles, which, as will be seen by the arrangement according to Figs. 1 and 2, is turnable around the axis *f* and guided between the parallel, tightly fitting guiding surfaces *e*.

As will be seen by Figs. 4 and 5 each segment part of the sieve-mantle of the centrifugal drum may consist of two or more parts, with the arrangement shown by way of example there are provided two halves, viz: a bottom one *a*¹, *b*¹ and so on, and a top one *a*², *b*² and so on. These two halves *a*¹, *a*² may be tightly connected or bolted together by any desired means *h*, so that the two halves *a*¹, *a*², *b*¹, *b*², may as one whole rigid part be regulated or adjusted around the pivoting point *f*, just as in the mode of con-

struction according to Figs. 1 and 2. In order to clean the closed or stopped up sieve-holes within the mantle automatically by means of centrifugal action, the bottom halves a^1 and the top halves a^2 may be arranged pivotally on the pins g , which pins g are arranged slidable within the segment parts, so that after separating the bottom mantle surface from the top one, the pins g 10 may be pushed into corresponding openings of the guides e , whereupon the bottom and top mantle surfaces a^1 , a^2 , b^1 , b^2 and so on may, after loosening the segment parts from their mounting on the axis f , be turned 15 through an angle of 180°, by which means the inner mantle surfaces i according to Fig. 4 will come to lie on the outside, as seen by Fig. 5.

Thus the effect is obtained that the stopped 20 up and closed sieve-holes are automatically cleaned by the centrifugal action.

What I claim is:

1. A centrifugal machine of the character described comprising, a plurality of mantle 25 segments, and a plurality of mantle segment guides, said segments being pivotally mounted to swing between adjacent guides and said guides having parallel faces adapted to contact continuously with the sides of the 30 mantle segments.

2. A centrifugal machine of the character described comprising, a plurality of mantle segments, and a plurality of mantle segment guides, each said segment including two 35 axles and an endless band movable thereabout and pivotally mounted to swing between adjacent guides, and said guides having parallel faces adapted to contact continuously with the sides of said endless band.

40 3. A centrifugal machine of the character described comprising a plurality of mantle segments and a plurality of mantle segment guides, each said segment including a plurality of parts pivotally mounted to swing as 45 a whole between adjacent guides and each part being provided with independent pivots whereby said parts may be separately rotated through an angle of 180 degrees, and said guides having parallel faces adapted to 50 contact continuously with the sides of said segments.

In testimony, that I claim the foregoing as my invention, I have signed my name this 25th day of August 1932.
